Primary Examiner—Cynthia E. Ramirez(74) *Attorney, Agent, or Firm*—Foley & Lardner LLP(57) **CLAIM**

The ornamental design for a cart, as shown and described.

DESCRIPTION

FIG. 1 is a perspective view of an embodiment of a cart according to my new design;

FIG. 2 is a front elevational view of the cart shown in FIG. 1;

FIG. 3 is a rear elevational view of the cart shown in FIG. 1;

FIG. 4 is a left side elevational view of the cart shown in FIG. 1;

FIG. 5 is a right side elevational view of the cart shown in FIG. 1;

FIG. 6 is a top plan view of the cart shown in FIG. 1; and, FIG. 7 is a bottom plan view of the cart shown in FIG. 1. The broken line showing of some elements in the figures is for illustrative purposes only and forms no part of the claimed design.
